HOUSING FOR A RADIO TUNER OR THE LIKE

Gerald J. Golden and Tom T. Tsuji, Los Angeles, and
James E. Walker, Gardena, Calif., assignors to GW
Electronics, Inc., a corporation of California

Filed June 14, 1968, Ser. No. 12,352

Term of patent 14 years

Int. Cl. D14—03

U.S. Cl. D56—4

FIG. -1

FIG. -2

FIG. -3

FIG. -4

FIG. - 5

FIG. - 6

FIG. - 7

FIGURE 1 is a perspective view of the ornamental design of the housing in accordance with this invention;

FIGURE 2 is an elevational view of the right side of the housing of FIGURE 1;

FIGURE 3 is an elevational view of the left side of the housing of FIGURE 1;

FIGURE 4 is an elevational view of the rear of the housing of FIGURE 1;

FIGURE 5 is a plan view of the housing of FIGURE 1;

FIGURE 6 is a front view showing the operating controls and dial assembly; and,

FIGURE 7 is a bottom view of the housing in accordance with this invention.

The dominant features of our design are shown in solid lines in the drawing.

We claim:

The ornamental design for a housing for a radio tuner or the like, substantially as shown and described.
